UNITED STATES PATENT OFFICE.

JOSEPH FRANCIS BODY, OF PHILADELPHIA, PENNSYLVANIA.

HAIK-PIN.

1,103,393.

Specification of Letters Patent. Patented July 14, 1914.

Application filed June 29, 1910. Serial No. 569,597.

To all whom it may concern:

Be it known that I, JOSEPH FRANCIS BODY, citizen of the United States, residing at Philadelphia, in the county of Philadelphia and State of Pennsylvania, have invented certain new and useful Improvements in Hair-Pins, of which the following is a specification.

This invention relates to hair pins and has for its object the provision of a pin of simple and durable construction, capable of being readily inserted in the hair and which shall positively grip the strands of hair so as to effectually prevent accidental displacement of the pin.

A further object of the invention is to provide a hair pin, the hair engaging members or legs of which are undulated or corrugated longitudinally, the convex portions of the corrugations on one leg being arranged opposite to and overlapping the concave portions of the corrugations on the mating leg so that when the pin is inserted in the hair, the strands of hair will be threaded transversely across the pin and under one leg and over the other.

A further object is to form the legs of the hair pin with co-acting gripping jaws which serve to assist in preventing accidental displacement of the pin.

A further object is to provide a hair pin, the construction of which is such that the corrugations thereof tend to waive the hair and to hold the strands separated to permit the circulation of air through the hair.

A still further object of the invention is generally to improve this class of devices, so as to increase their utility, durability and efficiency, as well as to reduce the cost of manufacture.

Further objects and advantages will appear in the following description, it being understood that various changes in form, proportions and minor details of construction may be resorted to within the scope of the appended claims.

For a full understanding of the invention and the merits thereof, reference is to be had to the following description and accompanying drawings, in which:

Figure 1 is a perspective view of a hair pin constructed in accordance with my invention, showing the same in position on the hair; Fig. 2 is a front elevation of the hair pin, showing the passage of the strands of hair therethrough; Fig. 3 is a side eleva-

tion; Fig. 4 is a transverse sectional view taken on the line 4—4 of Fig. 2, and looking in the direction of the arrow; Fig. 5 is a front elevation, illustrating a modified form 60 of the invention; Fig. 6 is a side elevation of the hair pin shown in Fig. 5; Fig. 7 is a front elevation illustrating a further modification; Fig. 8 is a side elevation of Fig. 7; Fig. 9 is a front elevation illustrating a 65 still further modification.

Corresponding and like parts are referred to in the following description and indicated in all the views of the drawings by the same reference characters.

The improved hair pin forming the subject matter of the present invention comprises a body portion preferably formed of a single length of wire, gutta-percha, celluloid or other suitable material, bent upon 75 itself at 5 to produce spaced hair engaging members or legs 6. The material forming the legs 6 is crimped longitudinally to produce undulations or corrugations 7 extending laterally from the front and rear of the 80 hair pin, said corrugations being disposed in staggard relation with the convex portions of the corrugations on one leg arranged in transverse alinement with the concave portions of the corrugations on the mating 85 leg so that when the pin is inserted in the hair, the strands will extend under one leg and over the other, thus to effectually grip the hair and prevent accidental displacement of the pin, as best shown in Fig. 90 2 of the drawings. The material forming the legs 6 is also bent inwardly at a point near the closed end of the pin to form co-acting gripping jaws 8, which latter serve 95 to assist in preventing accidental displacement of the pin, there being similar jaws 9 formed in the legs near the free ends thereof.

It will here be noted that the inner walls of the legs 6 are smooth and unobstructed, as indicated at 10 so as to permit the ready 100 passage of the pin through the hair. It will also be noted that the corrugations on one leg overlap the corrugations on the mating leg so that said corrugations, by engagement with the hair, will tend to crimp the 105 same and hold the strands thereof separated to permit the circulation of air through the hair.

The walls of the hair pin between the gripping jaws 8 and closed end 5, are preferably devoid of corrugations so as to present a smooth surface for engagement with

the hand, said closed end forming in effect a finger piece, as shown.

In using the hair pin, the terminals 11 thereof are inserted in the hair and a slight longitudinal movement imparted to the closed end or finger piece 5 which causes the strands of hair to enter the corrugations on the legs 6 and by which they will be effectually gripped so as to prevent accidental displacement of the pin, the gripping jaws 8 and 9, by engagement with the hair, serving to assist in preventing accidental displacement of the pin, as before stated.

In Figs. 5 and 6 of the drawings, there is illustrated a modified form of the invention, in which one set of gripping jaws is omitted, the gripping jaws 8 at the lower end of the pin being deemed sufficient in conjunction with the corrugations to retain the pin in position on the hair.

In the form of pin shown in Figs. 7 and 8, the intermediate portions of the legs are provided with smooth, unobstructed faces 13, the corrugations or crimps being formed 25 in the legs on opposite sides of the smooth portions.

In Fig. 9 of the drawings, there is illustrated a still further modification, in which the hair engaging members or legs are first bent inwardly to form co-acting gripping jaws 14 and thence bent outwardly and inwardly on converging lines, as indicated at 15 to produce oppositely disposed gripping jaws 16, the material forming the legs being thence bent outwardly and inwardly to produce a third pair of gripping jaws 17 arranged in spaced relation to the free ends of the legs, as shown. In this form of the device, as well as in the forms previously described, the corrugations or crimps extend laterally from the front and rear faces of the hair pin and are arranged in overlapped relation so as positively to grip the hair.

The hair pins may be made in different sizes and shapes and constructed with any number of gripping jaws or said gripping jaws may be entirely omitted, the essential feature of the present invention residing in

the overlapped relation of the corrugations, 50 whereby the hair is effectually gripped between the same to produce the desired results.

Having thus described the invention, what is claimed as new is:

1. A hair pin formed from a single length 55 of material bent upon itself to produce spaced hair-engaging members having their intermediate portions crimped to form corrugations of uniform length and width, two of said corrugations near the free ends of 60 the hair-engaging members being bent inwardly at substantially right angles to the other corrugations to produce oppositely disposed gripping jaws having convex faces, the hair-engaging members for the entire 65 distance between the said gripping jaws and the free ends of the members being parallel and devoid of corrugations.

2. A hair pin formed from a single length 70 of material bent upon itself to produce spaced legs of equal length having portions thereof near the closed end of the hair pin bent inwardly to produce upper co-acting gripping jaws, the material forming the legs of the hair pin beneath said jaws being 75 crimped to form corrugations extending laterally from the front and rear of the pin, the convex portions of the corrugations of one leg being disposed opposite to and overlapping the concave portions of the 80 corrugations of the mating leg, the terminal corrugations being spaced from the free ends of the legs of the pin and bent inwardly at substantially right angles to the other corrugations to form oppositely disposed lower co-acting gripping jaws having 85 arcuate faces, the legs of the pin for the entire distance between the lower gripping jaws and the free ends of the legs being devoid of corrugations. 90

In testimony whereof, I affix my signature in presence of two witnesses.

JOSEPH FRANCIS BODY. [L. S.]
